US0D1080983S

(12) **United States Design Patent** (10) **Patent No.:** **US D1,080,983 S**
(45) **Date of Patent:** **** Jun. 24, 2025**

(54) **STAND LIGHT**

(71) Applicant: **MILWAUKEE ELECTRIC TOOL CORPORATION**, Brookfield, WI (US)

(72) Inventors: **Kyle Harvey**, Wauwatosa, WI (US); **Ross McIntyre**, Milwaukee, WI (US)

(73) Assignee: **MILWAUKEE ELECTRIC TOOL CORPORATION**, Brookfield, WI (US)

(**) Term: **15 Years**

(21) Appl. No.: **29/818,372**

(22) Filed: **Dec. 8, 2021**

Related U.S. Application Data

(63) Continuation of application No. 17/465,965, filed on Sep. 3, 2021, now Pat. No. 11,530,799, which is a continuation of application No. 15/686,990, filed on Aug. 25, 2017, now Pat. No. 11,112,096, which is a continuation of application No. 14/877,675, filed on Oct. 7, 2015, now Pat. No. 10,378,739.
